United States Patent

Des. 234,309
Patented Feb. 11, 1975

234,309

EXERCISING BAR

Norman E. Buchner, 2717 S. Florence Drive,
Tulsa, Okla. 74114

Filed Aug. 6, 1973, Ser. No. 385,876

Term of patent 14 years

Int. Cl. D21—02

U.S. Cl. D34—5 K

FIG. 1 is a side elevation view of an exercising bar showing my new design.

FIG. 2 is an enlarged left end view.

FIG. 3 is an enlarged right end view.

FIG. 4 is an enlarged cross-sectional view taken along line 4—4 of FIG. 1.

FIG. 5 is an enlarged cross-section view taken along line 5—5 of FIG. 1.

FIG. 6 is an enlarged cross-sectional view taken along line 6—6 of FIG. 1.

FIG. 7 is an enlarged cross-sectional view taken along line 7—7 of FIG. 1.

FIG. 8 is an enlarged cross-sectional view taken along line 8—8 in FIG. 1.

I claim:

The ornamental design for exercising bar, substantially as shown and described.
